United States Patent Office

Des. 183,267

Patented July 22, 1958

183,267

COMBINED COLLAPSIBLE TRANSPARENCY VIEWER AND PICTURE FOLIO OR THE LIKE

Samuel Raber, Beverly Hills, and Noel Adolph Petter,
Glendale, Calif.

Application May 10, 1957, Serial No. 46,094

Term of patent 14 years

(Cl. D61—1)

FIG. 1.

FIG. 2.

FIG. 3.

Fig. 1 is a top perspective view of a combined collapsible transparency viewer and picture folio as it appears in closed position;

Fig. 2 is a top perspective view thereof as it appears in an open position; and

Fig. 3 is another top perspective view thereof as it appears with the viewer in erected position.

The side opposite to that disclosed in Fig. 1 (not shown) is plain and unornamented.

We claim:

The ornamental design for a combined collapsible transparency viewer and picture folio or the like, as shown and described.
